UNITED STATES PATENT OFFICE.

DUNCAN FORBES, OF NEWARK, NEW JERSEY.

SASH-LOCK.

SPECIFICATION forming part of Letters Patent No. 710,189, dated September 30, 1902.

Application filed May 28, 1902. Serial No. 109,285. (No model.)

To all whom it may concern:

Be it known that I, DUNCAN FORBES, a subject of the King of Great Britain, residing at Newark, in the county of Essex and State of New Jersey, have invented certain new and useful Improvements in Sash-Locks; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The objects of this invention are to provide a more secure and perfect fastener or lock for window-sashes, one adapted to more perfectly resist or prevent the opening of the window both from the inside and from the outside, to secure a device which will be of neat and ornamental appearance on the window and not detract from its finish, and to secure other advantages and results, some of which may be referred to hereinafter in connection with the description of the working parts.

The invention consists in the improved sash-lock and in the arrangements and combinations of parts of the same, all substantially as will be hereinafter set forth and finally embraced in the clauses of the claim.

Referring to the accompanying drawings, in which like letters of reference indicate corresponding parts in each of the several figures, Figure 1 is an elevation of the device arranged in connection with the upper and lower sashes of a window. Fig. 2 is a section of the same, taken at line x of Fig. 1 and showing the parts in their locked relation. Fig. 3 is a similar section showing the parts unlocked. Fig. 4 is a plan of the same. Fig. 5 is a plan showing the parts with the outer casing removed. Fig. 6 is a section of Fig. 5, taken at line y. Fig. 7 is a perspective view of the upper-sash member of the device. Fig. 8 shows a perspective view and side elevation of the locking-bolt. Fig. 9 is a perspective view of the lower-sash member, from which the locking-bolt has been withdrawn. Fig. 10 is an inside perspective view of the outer casing, and Fig. 11 is a perspective view of the lower-sash member complete with the locking-bolt in place.

In said drawings, a indicates a portion of the lower sash and b a portion of the upper sash, and upon the meeting-rails of said sashes are arranged, respectively, the upper-sash member c of the lock and the lower-sash member d.

The upper-sash member c comprises a single casting, (shown more clearly in Figs. 5 and 7,) having a downwardly-projecting face-plate c', which is perforated, and thus adapted to be secured against the inner face of the rail b, as shown in Fig. 2. The said casting is also provided with a pair of ears c² c², lying in a plane at right angles to the plane of the face-plate c', which ears extend outward and form a recess c³ between for a purpose hereinafter referred to. Between the said ears c² is formed a loop c⁴, adapted to receive the locking-bolt e. The ears c² are perforated to receive screws by means of which the member c is fastened to the rail, the screws being arranged at right angles to the screw through the plate c', and thus the upper-sash member of the lock is firmly fastened in place and cannot easily be withdrawn, even when the outer case is not in place.

The lower-sash member consists of a single casting and a bolt e, adapted to slide therein, the said casting being shown more clearly in Fig. 9, where d' is the downwardly-extending ear or plate, adapted to lie on the outer face of the meeting-rail of the lower sash and be secured thereto. d² is the body-plate of said casting, adapted to lie upon the top of the said meeting-rail and be screwed thereto from the top. The said body-plate d² is grooved, as at d³, Fig. 9, and provided with a loop d⁴, and in the groove and loop the bolt e slides to and from the upper-sash member c. At the inner corners on the under side of the plate d² are formed recesses d⁵, adapted to receive certain lugs formed on the outer casting, as hereinafter described. At one side of the groove d³ is formed a post d⁶ and a keyway d⁷, the post being adapted to enter the barrel of the key and the keyway d⁷ serving to receive the bit of the key. The lock-bolt e is formed to nicely fit the groove d³ and loop d⁴ of the casting d. Said bolt at one side is provided with recesses f, Figs. 8 and 11, adapted to receive the bit of the key when the latter is turned on the post d⁶. At the opposite

side the said bolt is provided with a pintle e' , Fig. 8, by which the bolt is prevented from being withdrawn from its casing or member. At its projecting end the said bolt is recessed, 5 as at e^2 , to receive a stay projection of the outer casing, as will be hereinafter described. The parts are so arranged as that by applying the key g to the post d^6 and turning the same the lock-bolt e is moved forward into 10 the loop c^4 and the sashes are thus locked. A second turn of the key g when the outer casing h is in position serves to throw the bolt into engagement with the said outer casing h to lock the same in place. When un- 15 locked, the outer casing is detachable from the sash member $c d$, and thus it may be removed from the sashes for the purposes of polishing or otherwise. The said outer casing h comprises a single box-like piece of 20 metal, preferably bronze or brass, as shown in Fig. 10, and provided at its inner side near the lower edges with inner projections or lugs $h' h^2$. The projections h' are arranged at the corners of the box or case and are adapt- 25 ed to slide into the recesses d^5 of the lower-sash member, while the lug or projection h^2 is adapted to fit between the ears $c^2 c^2$ of the upper-sash member. The top of the box or casing is suitably provided with a key- 30 hole h^3 , Fig. 4, adapted to permit the passage of the key through said case onto the post d^6 . The casing h is arranged first on the member d when the upper sash is a little low, as in Fig. 3, the said casing then being thrust out- 35 wardly and the lugs h' entering the recesses d^5 . Afterward the upper sash is raised, and the lug h^2 enters between the ears c^2 . The bolt e is then pushed outward by the key and passes over the projection h^2 , so that the cas- 40 ing cannot be removed, the said casing thus preventing any outside manipulation whatever or manipulation from the inside except by those in control of the key, thus serving to secure the sashes against either outside or in- 45 side manipulation and preventing carelessness of servants within the house in leaving, for example, the windows open when the mistress of the house is absent, as will be understood.

50 Having thus described the invention, what I claim as new is—

1. The combination with the upper and

lower sash members and a bolt for fastening the said parts together, of a casing adapted to be secured over the said members, and 55 locked thereto substantially as set forth.

2. The combination with the upper and lower sash members, one of the said members having a keyway or means for controlling the movements of the key and a lock-bolt having recesses to receive the bit of the key, said lock-bolt being adapted to move from one member into locking relation with the other member and thence into locking relation with the casing, of said casing adapted 60 to be secured by said lock-bolt over said lock members, substantially as set forth.

3. The combination with the sash members, and a lock-bolt slideable on one member into locking engagement with the other, of a 70 casing adapted to inclose both of said members and to be locked by said bolt and key for operating the bolt and locking all said parts together, substantially as set forth.

4. The combination with the sash mem- 75 bers having loops and ways for a locking-bolt, and a casing of said locking-bolt having separate recesses f, f , to receive the bit of the key and a key for moving said bolt from the loop on one member into the loop of the other, 80 the said bit when first rotating with the key being adapted to enter one recess and throw the bolt to lock the sash members together and, on the second turning, to enter the next recess in order and throw the bolt into locking 85 engagement with the casing, substantially as set forth.

5. The combination with the sash mem- 90 bers having loops and slideways and one of said members having a keyway, a bolt ar- ranged and adapted to be moved on said slide- ways and in said loops to lock said members together and a casing inclosing said members and having projections to engage one of said members and said bolt and be locked upon 95 said members substantially as set forth.

In testimony that I claim the foregoing I have hereunto set my hand this 17th day of May, 1902.

DUNCAN FORBES.
